LIMITING SPEED GOVERNOR

George P. Hanley, Northville, and Kenneth J. Winkel, Detroit, Mich., assignors to General Motors Corporation, Detroit, Mich., a corporation of Delaware

Filed Aug. 30, 1961, Ser. No. 135,031

8 Claims. (Cl. 73—531)

This invention relates to a governor for an internal combustion engine and more particularly to a limiting speed governor having an operator actuated linkage normally controlling the desired speed and load fuel requirements of an internal combustion engine between idle and maximum speed limits maintained by the governor mechanism.

The invention contemplates an improved governor of the type indicated which is of relatively simple and inexpensive construction, permits maximum versatility in meeting the mounting and speed and load requirements of different engine installations, and provides a fuel controlling linkage and speeder spring mounting arrangement permitting maximum accessibility for inspection, maintenance and adjustment.

The foregoing and other objects, advantages and features of the invention will be more thoroughly understood from the following description of a preferred illustrative embodiment, having reference to the accompanying drawings in which:

FIGURE 1 is an elevational view of a governor embodying the invention with portions of the governor being broken away and shown in detailed section;

FIGURE 2 is a view of the governor speed responsive mechanism shown partially in section and taken substantially in the direction of the arrows and in the plane of the line indicated at 2—2 in FIGURE 1;

FIGURE 3 is a top elevational plan view of the governor and fuel controlling linkage; and

FIGURE 4 is a side elevational plan view of the control linkage.

Referring more particularly to the drawings, a governor incorporating the invention is indicated generally at 10. This governor is similar in external configuration and mountable on an internal combustion engine in the same manner as to that shown and described in copending United States patent application Serial No. 83,651, entitled "Variable Speed Governor," and filed January 19, 1961, in the names of George P. Hanley and Charles E. Sloan.

The governor 10 includes a housing comprising a bell-shaped base member 12 and a control head or support member 14 interconnected by a housing sleeve 16. These housing components are identical and interchangeable with those of the variable speed governor of the above-identified application. The housing base and control head are secured for the front of an engine timing gear housing 8 which is in turn secured to the rear end of the internal combustion engine. The housing members 12 and 14 are preferably permanent mold light metal castings with the intermediate housing sleeve 16 being cut from tube stock to meet the governor mounting requirements for a given engine. A centrifugal flyweight mechanism A is rotatably mounted in the base housing member and the head 14 supports a speeder spring and fuel control linkage B.

As best seen in FIGURES 1 and 2, the flyweight mechanism A comprises a shaft 18 which is splined at 19 for driving connection to a crankshaft driven timing gear, not shown. The opposite end of the shaft 18 is journaled by a plain bearing 20 mounted in the smaller closed end of the bell housing 12. The shaft 18 is journaled adjacent its gear mounting end by a ball-type bearing 22

2

carried by a supporting carrier on spider member 24. This bearing carrier is supported within the larger open end of the bell housing 12 and telescopically pilots the flyweight mechanism and bell housing in mounting assembly with respect to an opening 26 provided in the timing gear housing 8. A flyweight carrier 28 is secured to the shaft 18 by a hub 30. The carrier is preferably of cast configuration having a perforated spider portion 31 secured to the shaft driven hub 30 and four angled and equiangularly spaced arms 32 which extend longitudinally of the struts between the several spider openings. These carry pivot pins 33 and 35 which pivotally mount two pairs of low and high speed flyweight assemblies 34 and 36, respectively. The low speed flyweights 34 are pivotally mounted by the pins 33 for outward swinging movement about parallel axes spaced on diametrically opposite sides of the shaft 18. The high speed flyweights are similarly mounted by the pins 35 for outward swinging movement about parallel axes disposed at ninety degrees to those of the low speed weights.

The flyweight assemblies 34 and 36 are preferably fabricated as shown from a plurality of stamped plates which may be color coded to indicate different materials and individual masses. These plates are selected in assembly to provide the various flyweight masses required for different engine applications. To provide adequate low speed governor response, the low speed flyweights are of substantially greater mass than the high speed weights 36. Abutment toes 38 and 40 are formed on the rear of the carrier spider 31 and abut end plates 42 and 44 of the high and low speed flyweights, respectively, to limit their speed responsive outward movement. The end plates 42 and 44 are preferably made of steel and have inwardly extending lever arms 46 and 48 thrustably engageable with a thrust collar or washer 50 secured on the adjacent end of a riser sleeve 52 which is slidably mounted on the engine driven shaft 18. The lever arms 46 and 48 thus transfer the speed responsive outward movement of their respective flyweights to the riser sleeve 52 causing it to shift to the right as viewed in FIGURE 1. The low speed lever arms 46 are somewhat shorter than the lever arms 48 of the high speed flyweights. As the engine throttle control is advanced to increase the engine fuel supply and thereby engine speed above the idle range maintained by the governor, the lever arm differential and high mass of low speed flyweights permits them to swing outwardly into abutment with the spider toes 38 and 40. Further speed responsive movement of the riser sleeve is thus limited to the speed responsive centrifugal action of the high speed flyweights 36.

The speed responsive flyweight motion imparted to the riser sleeve is transmitted through a second thrust collar 54 and an anti-friction bearing 56 carried by the opposite end of the riser sleeve to a yoked lever member 58 suitably secured to the adjacent lower end of a shaft 60. The shaft 60 extends through the housing sleeve 16 and is journaled adjacent its ends by bearings 62 and 64 carried by the base housing member 12 and the control head member 14, respectively. This shaft provides an operative connection intermediate the centrifugal mechanism A and the speeder spring and fuel controlling linkage means B.

The speeder spring and fuel controlling linkage B includes a lever 66 which has a hub 68 suitably secured to the upper end of the power shaft 60 for speed responsive movement therewith. The lever 66 has an arm 70 having an upstanding flange 71 distal from its hub 68. The flange 71 serves to support an eye bolt 72 which is adjustable relative thereto by lock nuts 73 and 73'. The eye bolt anchors one end of a relatively low rate helical spring 74. The spring 74 serves as an idle speeder

spring and is tensively interposed between the eye bolt 72 and one arm 76 of a speeder spring biased lever 78. The lever 78 has a hub 80 journaled on the upper end of the power shaft 60 by a flanged Teflon bearing 82 for limited angular movement relative to the lever 66. The speeder spring lever 78 has a second arm 84 having a flange 85 extending upwardly therefrom. The flange 85 supports a second eye bolt 86 which is adjustable relative thereto by lock nuts 87 and 87'. The eye bolt 86 engages the adjacent end of a second helical speeder spring 88. The spring 88 is of somewhat higher rate than the spring 74 and serves to establish the higher speed maintained by the governor mechanism. The spring 88 is tensively interposed between the eye bolt 86 and a stationary support flange or arm 90 extending laterally and upwardly from the bottom of a closed loop bracket member 92 embracing the speeder spring 88. The bracket 92 is in turn supported above the control head support member by a pedestal member 94. A second support flange 96 extends laterally and upwardly from the upper loop portion of the bracket member 92 and threadably supports a bolt 98. The bolt 98 is maintained in its adjusted position by a lock nut 100 and serves as an adjustable stop engageable with the flange 85 thereby limiting the maximum fuel controlling position of the speeder spring lever 78.

The spring biased lever 78 has a limited lost motion connection with the speed responsive power lever 66. This lost motion connection includes a depressed tang 102 which is carried by the lever 78 and projects downwardly into a slot 104 formed in the lever 66 adjacent its power shaft mounted end. During operation of the engine above its idle speed range, speed responsive movement of the power lever is counterclockwise of its idle speed position shown in FIGURE 3 and causes the side wall 106 of the slot 104 to engage the tang 102. Such engagement causes the speeder spring lever 78 to rotate in unison with the power lever 66 against the biasing action of the high speed speeder spring 88. During idle speed engine operation, the several governor and fuel control linkage elements are maintained substantially as shown in the accompanying drawings with initial speed responsive movement of the power lever being opposed solely by the idle speeder spring 74.

An intermediate arm or boss 108 on the power lever 66 carries a pivot post 110 which extends upwardly and pivotally supports a floating differential lever 112 intermediate its ends. The lever 112 has a downwardly extending arm 114 pivotally connected by a ball-and-socket joint 116 to one end of a link 118. The distal end of the link 118 is connectable to a suitable fuel supply control means such as the fuel supply controlling racks of a plurality of unit fuel injectors, not shown. The other arm 120 of the lever 112 carries a pin 122 which pivotally engages a lost motion slot 124 formed in the adjacent end of a bell-crank throttle lever 126. The lever 126 is pivotally supported at 128 on a stationary support arm 130 extending from the closed loop bracket member 92. The other arm of the lever 126 is pivotally connected by a ball-and-socket connection 132 to one end of a manually operable link 134 for movement between idle and full-fuel controlling positions indicated in FIGURE 3.

Movement of the lever 126 within such limits normally controls the fuel supply controlling position of the floating differential lever 112 between the idle and maximum engine speed and load limits maintained by the governor. When the lever 126 is in its idle position, the centrifugal biasing action of the flyweights 34 and 36 is equalized by the low speed speeder spring 74 thereby shifting the pivot post 110 in accordance with variations in the engine idle speed. Such movement of this pivot post serves to shift the fuel controlling position of the differential lever 112 about the pivot 122 to maintain the minimum speed corresponding to the adjusted biasing action of

the idle speeder spring. As the lever 126 is rotated toward its full fuel controlling position, the resultant increase in engine fuel supply increases the engine speed. The resultant increase in speed responsive movement of the power lever 66 effects engagement between the side wall 106 of the slot 104 and the tang 102. After such engagement, further speed responsive movement of the lever 66 is opposed by the speeder spring 88. Such movement of the lever 66 also serves to shift the fuel supply controlling differential lever 112 in a decreasing fuel direction until a fuel supply rate is achieved sufficient to maintain the high speed weights and speeder spring in force equilibrium at an engine speed corresponding to the selected position of the lever 126. As the engine approaches its maximum governed speed upon either a reduction in load or movement of the lever 126 to its full fuel position, the effected movement of the power lever pivot post 110 carries the differential fuel controlling lever 112 in a decreasing fuel direction until a maximum speed limiting equilibrium condition is obtained between the centrifugal biasing action of the high speed flyweights 36 and speeder spring 88.

In the illustrative embodiment, an engine shutdown control is operable to shift the link 118 to a no-fuel supply position independently of the position of the throttle control lever 126 and of the speed maintaining action of the governor. This shutdown control comprises a plate member 136 which is secured to and extends laterally from the fuel controlling link 118. One end of a flexible actuating wire 138 extends through an opening provided in one arm of the plate member 136 and carries an abutment collar 140. Under engine operating conditions, this collar is normally spaced from the plate member to permit unrestricted fuel supply controlling movement of the link 118. The wire 138 extends through a flexible sheath 142 to a suitable operating knob, not shown, mounted on the engine control panel, also not shown. The governor adjacent end of the sheath 142 is supported as shown in FIGURE 1 by a bracket assembly 144 secured to the side face of the control head member 14.

Upon operator actuation of the wire 138 in a shutdown effecting direction, the thrust collar 140 engages the plate member 136 and thus carries the fuel controlling link 118 to its fuel-off position wherein the other arm of the plate member 136 engages a limit screw 146 threadably supported by a flange 148 upstanding from the control head member 14. The limit screw 146 thus prevents overtravel of the fuel controlling linkages and injector control racks beyond their fuel-off positions. As the shutdown plate member 136 approaches such engagement with the limit screw 146, it first engages a buffer spring 150 carried by the limit screw. Shutdown effecting movement of the link 118 is normally accomplished under equilibrium speed conditions and is maintained against the biasing action of the high speed speeder spring 88. Upon release of the shutdown control knob the fuel controlling linkage is actuated in an increasing fuel direction as the speeder spring 88 carries the flange 85 of the spring biased lever 78 into engagement with the bolt 98. Such movement of the lever 78, of course, conditions the governor and the associated fuel supply controlling linkages for re-starting the associated engine.

From the foregoing description, it will be seen that the preferred illustrative embodiment provides the several stated objectives and advantages of the invention and that various modifications and changes might be made therein without departing from the spirit and scope of the invention as defined in the following claims.

We claim:

1. A control mechanism operable to govern an engine at a low idle speed and at a higher maximum speed with speed modulated manual control of fuel supply for intermediate speeds, said control mechanism comprising an engine speed responsive means including a first lever piv-

otal in response to changes in engine speed, a second lever pivotally mounted in coaxial pivotal relation to the first lever and having a limited lost motion driving connection therewith, said first lever having an upstanding arm at its end distal from its pivotal end, said upstanding arm being in substantially parallel spaced relation to a first arm on the second lever, an idle speeder spring tensively and adjustably interposed between the first arm of the second lever and the upstanding arm of the first lever, said second lever having a second upstanding arm substantially parallel to the upstanding arm of the first lever and perpendicular to and opposite the first lever arm of the second lever, a support member spaced from the second upstanding arm, a high speed speeder spring tensively and adjustably interposed between the second upstanding arm and the support member, an adjustable stop member engageable with the second upstanding arm to define an idle speed limit position for said second lever wherein the idle speed responsive range of movement of the first lever is incapable of driving said second lever through the lost motion connection, a third differential floating lever pivotally supported on said first lever intermediate its ends and between said speeder springs, one arm of said third lever being pivotally connectable to one end of a fuel regulating linkage and movable between no-fuel and full-fuel supply controlling positions, a fourth throttle control lever pivotally mounted on said support member and having one arm swingable above said floating differential lever, said fourth lever arm having a lost motion pivotal connection with the other arm of said floating differential lever and said fourth lever being operably connectable to manual control means and movable between idle and full-fuel supply positions.

2. An engine control mechanism operable to maintain engine idle and maximum speeds and having speed modulated manual control of the engine fuel supply for intermediate engine speeds, said control mechanism comprising a first lever pivotal in response to changes in engine speed, a second lever pivotally mounted in coaxial pivotal relation to the first lever, a limited lost motion driving connection between said first and second levers, an idle speeder spring tensively interposed between a first arm on the second lever and said first lever distal from its pivotal axis, a support member spaced from a second arm on the second lever, a high speed speeder spring tensively interposed between said second arm and the support member, a stop defining an idle speed limit position for said second lever wherein the idle speed responsive range of movement of the first lever is incapable of driving the second lever through the lost motion connection, a third lever pivotally mounted on the first lever for swinging movement between said speeder springs, one arm of said third lever being pivotally connectable to one end of a fuel regulating linkage movable between no-fuel and full-fuel supply controlling positions, a fourth lever pivotally mounted on said support member and having one arm swingable above the third lever, said fourth lever arm having a limited lost motion pivotal connection with the other arm of the third lever and said fourth lever being operably connectable to manual control means and movable between idle and full-fuel supply positions.

3. An engine control mechanism operable to provide speed modulated manual control of engine fuel supply between idle and maximum engine speed limits, said control mechanism comprising a first lever pivotal in response to changes in engine speed, a second lever coaxially pivoted and having a limited lost motion driving connection with said first lever, an idle speeder spring tensively interposed between a first arm on said second lever and the first lever distal from its pivotal axis, said idle spring biasing said first lever in opposition to its speed responsive pivotal movement, a stationary support spaced from a second arm on the second lever, a high speed speeder spring tensively interposed between said second arm and said support, a stop defining an idle

speed limit position for said second lever wherein the idle speed responsive range of movement of the first lever is incapable of driving the second lever through the lost motion connection, said high speed speeder spring 5 biasing the second lever toward said limit position and acting through said connection to bias said first lever in opposition to its speed responsive movement beyond its idle speed range, a third lever pivotally mounted on the first lever and having one arm pivotally connected to one end of a fuel regulating link movable between no-fuel and full-fuel supply positions, and a fourth lever pivotally mounted on said support and having a limited lost motion pivotal connection with another arm on said third lever, said fourth lever being operably connectable to 10 manual control means and movable between idle and full-fuel supply controlling positions.

4. In an engine speed control mechanism operable to provide speed modulated manual control of fuel supply between idle and maximum engine speed limits, a first lever pivotal in response to changes in engine speed, a second lever coaxially pivoted and having a limited lost motion driving connection with said first lever, said first lever having an upstanding arm spaced from a first arm on said second lever, an idle speeder spring tensively interposed between the first arm on the second lever and the upstanding arm on the first lever, said idle spring 15 biasing the first lever in opposition to its speed responsive movement, said second lever having an upstanding arm opposite and perpendicular to its first lever arm, a stationary bracket member spaced from the upstanding arm of the second lever, a high speed speeder spring tensively interposed between the bracket member and the upstanding arm of the second lever, an adjustable stop member carried by said bracket member and engageable 20 with the upstanding arm of the second lever, said stop defining an idle speed and maximum fuel controlling limit position for the second lever wherein the idle speed responsive range of first lever movement is incapable of driving the second lever through the lost motion connection, a third lever pivotally mounted on said first lever and having one arm pivotally connected to one end of a fuel regulating linkage movable between no-fuel and full-fuel supply controlling positions, and a fourth lever pivotally mounted on said bracket member and having a 25 limited lost motion pivotal connection with another arm on the third lever, said fourth lever being connectable to manual control means and movable between idle and full-fuel supply controlling positions.

5. In an engine limiting speed governor, a housing mountable on an associated engine, centrifugal means 30 mounted within said housing comprising a first shaft journaled within said housing and drivingly connectable to the engine, a flyweight carrier mounted on said first shaft, a pair of low-speed bell crank flyweights pivotally supported on diametrically opposite sides of said carrier 35 for outward swinging movement relative thereto, a second pair of high-speed bell crank flyweights pivotally supported on diametrically opposite sides of said carrier for outward swinging movement normally of said low speed flyweights, said carrier having abutments successively 40 limiting the speed responsive outward movement of said low and high speed flyweights upon operation of the engine above its idle and maximum speed limits, a second output shaft journaled in said housing and operably connected for pivotal movement in accordance with the 45 speed responsive outward movement of the flyweights, said second shaft projecting at one end beyond said housing, a first lever secured to the projecting end of said second shaft for speed responsive movement therewith, a second lever coaxially pivoted and having a limited lost motion connection with the first lever, said first lever having an upstanding arm at its end distal from the pivotal axis, an idle speed speeder spring tensively 50 interposed between a first arm on the second lever and the upstanding arm on the first lever and biasing said first lever in opposition to its idle speed responsive move-

ment, said second lever having a second upstanding arm perpendicular to its first lever arm and extending in substantially parallel spaced relation to the upstanding arm of said first lever, a closed loop bracket member having a plurality of support arms extending therefrom and mounted on the housing in spaced relation to the upstanding arm of the second lever, a high speed speeder spring embraced by said bracket member and tensively interposed between a support arm thereon and the upstanding arm of the second lever, a stop member threadably supported by a second arm on said bracket member and engageable with the upstanding arm of the second lever to define an idle speed and maximum fuel supply controlling limit position wherein the idle speed responsive range of movement of the first lever is rendered incapable of establishing driving engagement through said lost motion connection, said high speed speeder spring biasing the second lever toward its stop limited position and acting through said lost motion connection to bias said first lever in opposition to its speed responsive movement beyond its idle range, a third differential floating lever pivotally supported on said first lever and having an arm pivotally connectable to one end of a fuel regulating linkage movable between no-fuel and full-fuel supply positions, and a fourth throttle control lever pivotally mounted on said bracket member and having a pin-and-slot lost motion pivotal connection with another arm of said floating differential lever, said fourth lever being operably connectable to manual control means and movable between idle and full-fuel supply positions to shift the fuel supply controlling position of the differential lever as modulated by the engine speed responsive movement of the first lever to maintain a selected constant engine speed corresponding to the equilibrium force conditions obtained between the flyweights and speeder springs.

6. An engine limiting speed governor operable to maintain engine idle and maximum speed limits and having speed modulated manual throttle control of fuel supply at all intermediate speeds, said governor comprising a housing mountable on an associated engine, centrifugal means mounted within said housing and including a first shaft journaled within said housing and drivingly connectable to the engine, a flyweight carrier mounted on said first shaft, a pair of low speed flyweights pivotally supported on diametrically opposite sides of said carrier for outward swinging movement relative thereto, a second pair of high speed flyweights pivotally supported on diametrically opposite sides of said carrier for outward swinging movement intermediate said low speed flyweights, said carrier having stop abutments successively limiting the speed responsive outward movement of said low and high speed flyweights upon operation of the engine above its idle and maximum speed limits, a second output shaft journaled in said housing and operably connected for pivotal movement in accordance with the speed responsive outward movement of the flyweights, said second shaft projecting at one end beyond said housing, a first lever secured to the projecting end of said second shaft for speed responsive swinging movement therewith, a second lever coaxially pivoted and having a limited lost motion driving connection with the first lever, an idle speed speeder spring tensively interposed between a first arm on said second lever and said first lever distal from its pivotal axis, said idle spring biasing said first lever in opposition to its speed responsive movement, a bracket member mounted on said housing and spaced from a second arm on the second lever, a high speed speeder spring tensively interposed between said second arm and said bracket member, a limit stop member threadably supported by said bracket member and engageable with said second arm to define an idle speed limit position wherein the idle speed responsive range of first lever movement is rendered incapable of establishing

driving engagement through said lost motion connection, said high speed speeder spring biasing the second lever toward its stop limited position and acting through said lost motion driving connection to bias said first lever in opposition to its speed responsive movement beyond its idle range, a third differential floating lever pivotally supported on said first lever and having an arm pivotally connectable to one end of a fuel regulating linkage movable between no-fuel and full-fuel supply positions, and a fourth throttle control lever pivotally mounted on said bracket member and having a pin-and-slot lost motion pivotal connection with another arm of said floating differential lever, said fourth lever being operably connectable to manual control means and movable between idle and full-fuel supply positions to shift the fuel supply controlling position of the differential lever as modulated by the engine speed responsive movement of the first lever to maintain a selected constant engine speed corresponding to the equilibrium force conditions obtained between the flyweights and speeder springs.

7. In an engine limiting speed governor, centrifugal means including an engine driven shaft, equiangularly spaced and paired low and high speed flyweights pivotally supported for outward swinging movement on diametrically opposite sides of said shaft, abutment means for successively limiting the speed responsive outward movement of said low and high speed flyweights upon operation of the engine above idle and maximum speed limits, a first lever operably connected for pivotal movement in accordance with the speed responsive outward movement of the flyweights, a second lever having a limited lost motion pivotal connection with the first lever, an idle speeder spring tensively interposed between a first arm on the second lever and the first lever and biasing the first lever in opposition to its increasing speed responsive movement, a support member spaced from a second arm on the second lever, an adjustable stop engageable with said second arm to define an idle speed and maximum fuel supply controlling limit position wherein the idle speed responsive range of first lever movement is incapable of effecting driving engagement through said lost motion connection, a high speed speeder spring tensively interposed between said second arm and the support member and biasing the second lever toward its stop limited position and acting through the lost motion connection to bias the first lever in opposition to its speed responsive movement beyond its idle range, a third lever pivotally supported on the first lever and connectable to a fuel regulating linkage movable between no-fuel and full-fuel supply controlling positions, and a throttle control member movable between idle and full-fuel positions and having a lost motion pivotal connection with the third lever, the fuel supply control positioning of the third lever by said throttle member being modulated by the engine speed responsive movement of the first lever to maintain a desired constant engine speed corresponding to the selected position of the throttle member and the equilibrium force conditions obtained between the flyweights and speeder springs.

8. An engine speed control mechanism operable to provide speed modulated manual control of the engine fuel supply to maintain desired constant speeds between idle and maximum engine speed limits, said mechanism comprising an engine speed responsive means including a first lever pivotal in response to changes in engine speed, a second lever having a limited lost motion pivotal connection with said first lever, a stop defining an idle speed limit position for the second lever wherein idle speed responsive first lever movement is incapable of effecting second lever driving engagement through the lost motion connection, an idle speeder spring interposed between and biasing the first lever in opposition to its speed responsive pivotal movement and biasing the second lever away from its stop limited position, a high speed speeder spring biasing the second lever toward its stop limited position and acting through the lost motion connection

to bias the first lever in opposition to speed responsive movement beyond its idle range, a third lever pivotally connected to the first lever and a fuel regulating link movable between no-fuel and full-fuel supply controlling positions, and a throttle member having a limited lost motion connection with said third lever and movable between idle and full-fuel supply controlling positions, the fuel supply control positioning of the third lever by the throttle member being modulated by speed responsive movement of the first lever to maintain a desired constant

5

engine speed corresponding to the selected positioning of the throttle member and equilibrium force conditions obtained between the speeder springs and the speed responsive movement of the first lever.
